corporation of Delaware

Application March 13, 1947, Serial No. 734,313

2 Claims. (Cl. 179—100.11)

1

This invention is directed to a radio-phonograph combination. More specifically it is directed to a radio-phonograph combination wherein maximum use is made, in phonograph operation, of circuits which have hitherto been considered useful only for radio reception.

It has been proposed in the past to reproduce sound records, recorded in the well known amplitude variation manner, by converting the mechanical displacements produced during the recording process into a variable frequency deviation of a predetermined radio frequency carrier. The frequency modulated carrier energy is then subjected to a detection process for converting the frequency deviations into corresponding amplitude variations. One of the most important advantages of this method is that a capacity pickup device can be employed with the variable frequency oscillator. This pickup device is highly economical compared to the relatively expensive types of electrical pickup devices employed in the usual conventional method of converting the sound vibrations into audio signal energy.

It is recognized, however, that arrangements of the character described are limited in their application because of the necessity of maintaining a high order of frequency stability of the frequency-modulated oscillator to prevent its drifting entirely out of the range of the associated detector circuit. This is further complicated by the fact that installations of the type wherein pickup units of economical construction may be used to advantage do not lend themselves to the economical inclusion of oscillators of sufficient stability. This fact has tended to limit the use of the economical capacity type pickup to the detriment of the industry at large.

An arrangement for eliminating the shortcomings of prior-art capacitive phonograph pickups is disclosed in my copending application for United States Letters Patent, Serial No. 660,944, now abandoned.

The object of this invention is to eliminate the need for a specific oscillator tube when using a capacitive phonograph pickup in a radio-phonograph combination.

The object of this invention is accomplished by a switching system whereby an amplifier tube and its associated circuits may be caused to function as a phonograph oscillator with a minimum of circuit deviation from conventional receiver design practice.

Other and further objects and advantages of this invention will be apparent from a considera-

2

tion of the following detailed description taken in connection with the accompanying drawing, the single figure of which is a schematic diagram of a circuit embodying the invention. It is to be expressly understood, however, that neither the description nor the drawing is intended to define the scope of the invention, reference for the latter purpose being had to the appended claims.

In the drawing there is illustrated a radio-phonograph combination in accordance with the instant invention.

In the drawing there is illustrated an intermediate-frequency amplifier comprising an electron discharge tube 10 having its anode 11 connected through the primary winding 12 of an intermediate-frequency transformer 13 to a source of voltage indicated +B. The control electrode 14 of the tube 10 is connected through a series combination of the resonant secondary circuit 15 of an I. F. transformer 16 and a condenser 17 to ground. The cathode 18 of the tube 10 is directly connected to the suppressor electrode thereof, and to ground through a parallel circuit comprising a condenser 20 and a resistor 21. The screen 22 is connected to the cathode 18 through a condenser 23 and to the source of voltage +B through a resistor 24.

The secondary winding 25 of the transformer 13 is connected, at one terminal thereof, to the anode 26 of a second electron discharge tube 27, and, at the other terminal thereof, to ground through a series combination of two resistors 28 and 29. The cathode 30 of the tube 27 is connected to the point of junction of the resistor 28 and 29. The junction of the winding 25 and the resistor 28 is connected to an output terminal 31 and to ground through a series circuit comprising a resistor 32 and a condenser 33. The cathode 30 of the tube 27 is additionally grounded through a series circuit comprising a condenser 35 and a resistor 34. A single pole double throw switch 37 has its arm 36 connected to the ungrounded side of the condenser 17 and its fixed contacts A and B respectively connected to the ungrounded sides of the resistor 34 and the condenser 33.

A second single pole double throw switch 38 has its arm 39 connected to the movable element 40 of a capacitive phonograph pickup, and its fixed contacts A₂ and B₂, respectively, connected to the control electrode 14 and ground. A third single pole double throw switch 41 has its movable arm 42 connected to the fixed element 43 of the capacitive phonograph pickup, and its fixed contacts A₃ and B₃, respectively, connected to

the anode 11 and ground. A stylus 44, secured operatively to the movable element 40, cooperates with the convolutions of a recorded track of a phonograph record 45.

In operation the switches 37, 38, and 41 are ganged so as to selectively contact the fixed contacts A₁, A₂, and A₃ or the contacts B₁, B₂, and B₃ respectively. With the ganged switches in the B position it will be manifest that the operation is that of a conventional radio receiver wherein the tube 10 serves as an I. F. amplifier and tube 27 functions as a diode detector. Audio output is obtained at the terminal 31, and AVC is applied to the tube 10 through the filter comprising the resistor 32 and the condenser 33.

With the ganged switches in position A, however, the capacitive pickup provides sufficient coupling between the anode 11 and the control electrode 14 to permit the tube 10 to operate as a tuned-plate tuned-grid oscillator with the varying capacity between the electrodes 40 and 43 causing a variation in the magnitude of the feedback voltage under the influence of the motion of the stylus 44. A grid-leak resistor 34 is brought into service as bias supply for the oscillator. Inasmuch as vibration in the capacity between the pickup elements 40 and 43 causes a variation of the magnitude of the feedback, it will be manifest that the bias voltage developed across the resistor 34 will have a correspondingly varying component. A series condenser 35 blocks the D. C. component of this voltage, and the A. C. component appears across the resistor 29 as an audio reproduction of the modulation on the record 45. The condenser 17 in parallel with the resistor 34 has a low impedance at the frequency generated by the oscillator, but a comparatively high impedance to the desired audio frequency signals and thus serves to eliminate any oscillator-frequency voltage which might otherwise appear across the resistor 29.

The variation of the feedback voltage of the oscillator produces a considerable amplitude modulation of the output of the oscillator, and this output is applied to the diode detector tube 27 through the transformer 43. Upon detection the audio-frequency modulation appears across the diode load resistor 28. The voltages across the resistors 28 and 29 are thus in series, and the output signal at the terminal 31 comprises the sum of the two audio signals, and is then ready

for amplification by the audio frequency amplifier of the receiver.

What is claimed is:

1. In combination, a radio frequency amplifier having input and output circuits, a network including an electro-mechanical transducer, switching means for connecting said network between said output and said input circuits in a regenerative sense, whereby said amplifier acts as an oscillator, a resistor, a second switching means ganged with the first named switching means and operative to connect the said resistor in the grid circuit of said amplifier as a grid-leak resistor when said network is connected, a detector, means coupling said output circuit to said detector and means combining additively the output of said detector and the alternating voltage developed across said grid-leak resistor.
2. In combination, a radio frequency amplifier having input and output circuits, a network including an electro-mechanical transducer, switching means for connecting said network between said output and said input circuits in a regenerative sense, whereby said amplifier acts as an oscillator, a resistor, a second switching means ganged with the first named switching means and operative to connect the said resistor in the grid circuit of said amplifier as a grid-leak resistor when said network is connected, a detector, means coupling said output circuit to said detector, a load resistor for said detector, a third resistor serially connected with said load resistor, means applying the alternating voltage developed across said grid-leak resistor to the junction of said serially connected resistors, and output terminals for said detector, said serially connected resistors being connected across said terminals.
